UNITED STATES PATENT OFFICE.

JESSE L. BLICKENSTAFF, OF NORTH MANCHESTER, INDIANA.

GATE.

SPECIFICATION forming part of Letters Patent No. 591,154, dated October 5, 1897.

Application filed July 10, 1896. Serial No. 598,745. (No model.)

To all whom it may concern:

Be it known that I, JESSE L. BLICKENSTAFF, a citizen of the United States, residing at North Manchester, in the county of Wabash 5 and State of Indiana, have invented certain new and useful Improvements in Gates; and I do hereby declare the following to be a full, clear, and exact description of the invention, such as will enable others skilled in the art to 10 which it appertains to make and use the same.

My invention relates to improvements in farm-gates, the object of the same being to provide an improved construction of gate which may be opened from either side and which is 15 kept closed and locked at all times, except when it is desired to pass through the same.

The invention consists of two posts, upon one of which the gate is hinged and to the other of which the gate is latched. The post 20 upon which the gate is supported is provided with a cross-arm at its upper end which has pulleys at each end, around which the cords or wires pass, one end of each of which cords is connected to the release-bar of the gate and 25 the other, after passing over suitable guide-pulleys, is connected to posts located on opposite sides of the gate. The release-bar referred to is mounted in suitable guide-bars on the side of the gate and has a projecting 30 arm or pin which is adapted to engage an angularly-disposed lug or projection on a lever, to which the latch-bolt is pivoted, so that when said release-bar is raised said latch-bolt is withdrawn from its engagement with a mortise in the post which it normally fits. 35

The invention is clearly illustrated in the accompanying drawings, in which—

Figure 1 represents in perspective my gate and its operative parts complete. Fig. 2 is a 40 side elevation showing the opposite side of the gate. Fig. 3 is a perspective view of the latch-post. Fig. 4 is a detail view in perspective of the release-bar. Fig. 5 is a similar view of the releasing-lever, showing its 45 connection with the latch-bolt.

Like reference-numerals indicate like parts in the several views.

My gate 1 is supported upon suitable hinges on the post 2 and is secured in locked position by the post 3. The post 2 is securely braced by means of a weight 4, buried in the ground, from which a guy-rope 5 passes, as

clearly shown in Fig. 1. The upper end of said post 2 is provided with a cross-head 6, which is slightly separated from the post 2 by 55 means of a block 7, inserted between it and said post. In the outer ends of the cross-head 6 are mounted pulleys 8 9, around which pass cords 10 11, respectively, which cords in turn pass over suitable pulleys in the posts 12 13, located on each side of the gate 1 and have connected to their outer ends weights 14, as clearly shown. The said post 2 is further provided with a roller 15, mounted in suitable brackets near the upper end of said 60 post, which roller serves the function of a brace for the operator in closing the gate.

The post 3 is provided with a longitudinal mortise 16 therein, with beveled edges on each side thereof, as clearly shown in Fig. 3 70 of the drawings. Pivotedly connected to the inner face of the post 3, at a point just below the mortise 16, is a block 17, whose lower end is heavier than the upper end, the said upper end being substantially a narrow strip 75 18, which when the gate is opened lies directly opposite the mortise 16, being held in such position by gravity. A suitable stop 18^a is provided for limiting the outward movement of the lower part of said block. The 80 latch-bolt 19 is adapted to fit the mortise 16 when in its closed position, and as the gate is adapted to swing in either direction the block 17 is provided for preventing the latch-bolt from passing in one direction or the other 85 beyond said mortise. When the same closes, the outer end of said latch-bolt comes in contact with the upper contracted portion 18 of the block 17 and forces it to one side beyond the mortise 16, permitting the said latch-bolt 90 to fall therein. This block operates in either direction in which the gate may be turned. When it is desired to open the gate, the latch-bolt is retracted, in a manner hereinafter described, beyond the inner surface of the block 95 17. The said latch-bolt 19 may be constructed of wood or iron, as desired, moves in suitable ways in the gate 1, and projects through a slot in the outer post of said gate. It is normally held in its outward position by means 100 of a spring 20, secured to said bolt and to the outer post of the gate. Its rear end is pivotally connected to a lever 21, fulcrumed in one of the cross-bars of the gate 1, which lever

- moves within a guide 22 at its upper end and is provided on one side with an angularly-disposed lug projection 23, as clearly shown in Fig. 5. The rear side of said lever 21 is 5 protected by a bar 24 of the same width, so that cattle or horses will not be able to operate the latch 18 by rubbing against the lever 21. On the opposite side of the gate to that on which the lever 21 is mounted is a release-bar 25, which moves in suitable guideways 26 26 on the cross-bars of the gate and is provided with a pin 27 on its inner side, which pin is adapted to engage the angularly-arranged lug or projection 23 on the lever 21. 10 15 The said release-bar is further cut away near its upper end, so that an inclined surface will be brought to bear against the upper guide 26 for the purpose of forcing the pin 27 against the under side of the lug or projection 23. 20 25 The lower end of said release-bar is further provided with a pin or arm 28, which projects outwardly therefrom and engages a pin 29 on the lower bar of the gate 1 for the purpose of throwing the upper end of said release-bar outwardly. 30 Hogs and other animals are prevented from raising the release-bar 25 by reason of the block 30, located on the under side of said bar. 35 Connected to the gate 1 is a bar or beam 31, which projects upwardly from the top of the gate and has a pulley 32 in its upper end, which is located directly over the upper end of the release-bar 25. 40 45 The cords 10 11 are connected together at a point near the pulley 32, and a single cord 33 extends downwardly therefrom and connects with a staple 34 on the upper end of the release-bar 25. 50 From the foregoing description, taken in connection with the accompanying drawings, it is thought that the operation of my invention will be readily understood. Briefly stated, however, it is as follows: If it is desired to open the gate by one approaching it, 45 it is merely necessary to pull one or the other of the cords 10 11, extending downwardly from the pulleys on the upper ends of one of the posts 12 13. This action will raise the release-bar 25, and through the engagement of the pin 27 thereon will cause the upper end of the lever 21 to be thrown forwardly, drawing back the lower end of said lever and withdrawing the latch-bolt 19 from the mortise or recess 16 in the post 3. A still further pressure on the cord 10 or 11 will, by reason of the angular direction in which said cords extend from the bar 31, open said gate in one direction or the other, according to which one 55 of the cords 10 11 is pulled. The means for closing the gate will be readily understood, and when the latch-bolt in the same is brought

opposite the mortise 16 in the post 3 the spring 19 on said latch-bolt will throw the latter into its locked position. 65

I have described my invention in its preferred form and realize that many slight changes might be made in many of the different parts. For example, the bar 31 might be secured to the gate 1 in an upright position 70 and double cords pass from the end of the bar 31 under a pulley on the end of said release-bar 25. Such obvious changes as these, however, are contemplated by me and are intended to be covered by this patent. 75

The ropes or wires are crossed behind post 2 if it is desired to swing the gate away from the operator.

Having now described my invention, what I claim as new, and desire to secure by Letters Patent, is—

1. The combination with a gate, a post upon which said gate is mounted and a latch-post for the same, of a latch-bolt slidingly mounted in said gate and adapted to engage a mortise or slot in said latch-post, a spring for normally holding said latch-bolt in its outer position, a lever to which said bolt is connected, an inclined lug or projection on said lever, a release-bar moving in guideways on said gate, a pin on said release-bar which is adapted to engage the lug on said lever and means, actuated from a distance, for raising and lowering said release-bar, substantially as and for the purpose described. 85 90 95

2. The combination with a gate, a post upon which said gate is supported and a second post to which said gate is latched, of a latch-bolt slidingly mounted in said gate, a spring for normally holding said bolt in its outward 100 position, a lever to which said bolt is pivotally connected, an angularly-arranged lug or projection on one side of said lever, a release-bar mounted in suitable guideways on said gate, a pin on said release-bar adapted to engage the lug on said lever, a beam secured to said gate and projecting upwardly therefrom, a pulley mounted in said beam just above said release-bar, a cross-head on the upper end of the post upon which said gate is supported, pulleys in the outer ends thereof, posts located on each side of said gate, cords passing over pulleys on said posts, pulleys on said cross-head, and a pulley on said beam and connected to the upper ends of said release-bar, substantially as and for the purpose described. 110 115 120

In testimony whereof I have signed this specification in the presence of two subscribing witnesses.

JESSE L. BLICKENSTAFF.
